United States Patent Office

Des. 183,089
Patented June 24, 1958

183,089

DRINKING FOUNTAIN

Ernst Alden Eriksson, Lexington, Mass., assignor to
Northern Industries, Inc., Milwaukee, Wis., a corpora-
tion of Wisconsin

Application April 12, 1957, Serial No. 45,714

Term of patent 3½ years

(Cl. D91—4)

Fig. 1

Fig. 2

Fig. 3

Fig. 1 is a view in side elevation of a drinking fountain embodying my new design;

Fig. 2 is a view in front elevation thereof with the cap element in closed position; and

Fig. 3 is a top plan view thereof.

The faucet and hose fragments shown in broken lines in Fig. 1 are for purposes of illustration only.

I claim:

The ornamental design for a drinking fountain, substantially as shown and described.
